UNITED STATES PATENT OFFICE

MCLEOD THOMSON, OF CHELSEA, NEW JERSEY, ASSIGNOR TO THE THOMSON RAIL CORPORATION, OF PHILADELPHIA, PENNSYLVANIA, A CORPORATION OF NEW YORK

RAIL-SPlicing STRUCTURE

Application filed June 16, 1930. Serial No. 461,555.

This invention relates to so-called head-free rail and joints for the same, and has for its general object to provide a structure which possesses greater strength than has heretofore been secured in that type of structure.

As is well known, the head of a headfree rail has the approximate conformation of an inverted pyramid which is truncated at its junction with the web of the rail, as disclosed, for example, in Thomson Patent No. 1,507,870, granted September 9, 1924. Thus, inwardly of the substantially vertical plane of the side of the rail head and above the horizontal plane of the head fillet of the rail, there is a space which is not entered by the flanges of wheels passing over the rail.

The general practice heretofore has been to terminate the top of the splice bar used with headfree rail at or below the horizontal plane of the head fillet of the rail, in order to provide wheel flange clearance above the head of the bar.

To those versed in the rail joint art it is appreciated that even a relatively slight increase in the height of a splice bar adds materially to its effective physical properties, particularly the desirable physical property of a high moment of inertia. Accordingly, it is an object of the present invention to increase the strength of the joint bars and to improve generally the physical properties of the whole structure by increasing the height of such bars, and to do this in a way which will provide ample wheel flange clearance above the bar, specifically by providing the bar with a formation at the top thereof which is adapted to occupy or extend through the previously mentioned space which is disposed inwardly of the vertical plane of the outer face of the rail head and above the horizontal plane of the uppermost portion of the rail head fillet.

Another object of the invention is to provide a splice bar for headfree rail having a greater bolting surface area than heretofore, particularly above the line of bolt holes, thereby to provide greater clearance below the head of the bar for the nuts and nut locks of the joint bolts and for the tool em-

ployed to turn the nuts, this being rendered possible by reason of the elevation of the head of the bar permitted by the increase in the height of the bar.

With the foregoing and other objects in view, the invention consists in the novel features of construction, combination and arrangement of parts as will be hereinafter more fully described, illustrated in the accompanying drawings and defined in the appended claims.

In the drawings, wherein are illustrated certain practical embodiments of the invention:—

Figure 1 is a bisected sectional view of a headfree rail joint constructed according to one practical embodiment of the invention; and

Figures 2, 3, 4, 5, 6, 7 and 8 are similar views illustrating other practical embodiments of the invention.

In each of the figures of the drawing the rail is designated as R, and the splice bar as B.

The type of rail with which the present invention is associated is the so-called head-free rail, an example of which is shown in the Thomson patent referred to, and which in comparison with the standard T-rail, omits the bottom corner structure of the T-rail, leaving at these locations in the headfree rail what may be termed a vacated space or area which is utilized to permit the bar head to be extended into or through said space or area to accomplish the objects herein stated. That is, in the headfree type of rail the head thereof has the approximate conformation of an inverted, truncated pyramid which, at its junction with the web 11, is merged into the latter by a fillet 12 forming in most instances in the present invention a fishing bearing for the inner projection 13 of the head 14 of the splice bar. In other words, beginning at a point spaced downwardly from the top of the rail, the side of the rail head is inclined inwardly as indicated at 15, which obviously results in a vacated area or space 16 being disposed inwardly of the plane of the substantially vertical, upper portion of the side of the rail and above the horizontal plane of the

uppermost portion of the fillet 12. Accordingly, by reason of such disposition of said space, or ordinarily vacated area, it is manifest that same is not entered by the flanges of wheels passing over the rail. Therefore, to take advantage of this condition, the present joint bar is provided with a top formation of metal, designated as 17 in each of the figures of the drawings, to extend into said space. Thus, as compared with the usual prior bar which terminates at its top substantially in or below the horizontal plane of the upper portion of the fillet 12, as illustrated by dotted lines in Fig. 5 of the drawings, the present bar is of increased height with a consequent proportionate improvement in its physical properties, especially as regards the moment of inertia, and, therefore, same is of increased strength and stiffness, particularly as regards its capacity to sustain vertical loads, all without reduction in the wheel flange clearance above the top of the bar.

Moreover, by reason of the increased height obtained by the formation 17 of metal at the top of the bar, the head of the bar may be proportionately elevated and a greater bolting surface area 18 obtained, particularly above the line of the bolt holes 19, to afford greater clearance below the head of the bar for the nuts and the nut locks of the usual joint bolts and for the tool employed to turn the nuts.

In the specific example of the invention illustrated in Fig. 1, the outer face of the splice bar is continuously flat as distinguished from the embodiments of the invention illustrated in Figs. 2 to 5 wherein the head of the bar extends outwardly as at 20 beyond the bolting surface 18, which construction is permitted by reason of the increased strength and stiffness of the bar afforded by the increased height thereof.

In the specific embodiment of the invention illustrated in Fig. 4 it will be noted that the portion of the head of the bar which extends outwardly beyond the plane of the substantially vertical upper portion of the side of the rail terminates at its top slightly above the horizontal plane of the uppermost portion of the head fillet 12 of the rail, or, in other words, substantially in a horizontal plane which would include the lower corner of a standard rail of equivalent weight as the rail R and indicated by the dotted lines 21, so that a wheel flange clearance is provided above the top of the bar equal to the clearance heretofore provided above the tops of prior bars employed for splicing standard rail. This clearance, at the same time, obviously is advantageously less than the clearance afforded by prior headfree bars which terminate at their tops substantially in the horizontal plane of the uppermost portion of the head fillet 12, inasmuch as it results in an increased height of the bar.

As a matter of fact it is permissible to extend the top of the bar B, which projects outwardly beyond the plane of the substantially vertical side portion of the rail above the plane of the top of the bar illustrated in Fig. 4 and still provide ample wheel flange clearance above the bar, and this is illustrated in Figs. 1, 2, 3 and 5 of the drawings, the dotted lines 22 in these figures illustrating that, if found to be necessary or desirable, the said outwardly directed top portions of the bars may be formed to provide wheel flange clearance.

With particular reference to Fig. 5 of the drawings it will be noted that the bar B may take loading engagement with the inclined face 15 of the rail instead of with the head fillet of the rail as illustrated in the other figures of the drawings, and in this connection, the inclined face of the rail may be rounded as shown to afford an ideal section for rolling and to provide an efficient fishing for the head of the splice bar. Furthermore, in this connection it is pointed out that while the usual practice heretofore has been to construct the splice bar to take loading engagement with the head fillet 12 of the rail, this is by no means essential, since a bar having a head formation of metal to extend into or through the vacated space or area 16, in accordance with the present invention, may have fishing contact at its head with the rail in any way desired, either with the head fillet 12 or above or below said fillet, anywhere within a zone indicated for example between the lines a—a and b—b— in Fig. 1 of the drawings.

Referring particularly to Fig. 6 of the drawings, it will be noted that the inclined side face 15^a of the rail is of dished or concave construction. This serves to increase the area of the vacated space 16^a to permit a larger formation of metal 17^a on the head of the bar and at the same time provides a greater surface area of fishing between the bar and the rail.

Fig. 7 illustrates that the bar B may be constructed to lie entirely inward of the vertical plane of the side of the rail head, in which connection it will be understood, of course, that the present bar may be of any cross-sectional shape desired, irrespective of the type of fishing contact it may have with the rail.

Fig. 8 illustrates the adaptability of the present joint structure to being insulated, a head piece of insulation 23 being interposed between the head of the bar and the rail and extending into the space 16, and a base piece of insulation 24 being interposed between the rail flange and the foot flange of the bar.

Without further description it is thought that the features and advantages of the invention will be readily apparent to those skilled in the art, and it will of course be

understood that changes in the form, proportion and minor details of construction may be resorted to, without departing from the spirit of the invention and scope of the appended claims.

5 I claim:—

1. A rail splicing structure including the rail having the bottom corners of its head truncated, and a connecting splice bar having 10 a head member provided with a formation of metal extending into the space or area vacated by the head truncations.

15 2. A rail splicing structure including the rail having the bottom corners of its head truncated, and a connecting splice bar having a head member provided with a formation 20 of metal extending through the space or area vacated by the head truncations.

25 3. In a rail joint, the rail having a head approximating in cross sectional shape an inverted truncated pyramid providing a space disposed inwardly of the vertical plane of the side of the rail and above the horizontal plane of the head fillet of the rail, and a splice bar provided at its top with a formation of metal 30 extending into said space.

35 4. In a rail joint, the rail having a head approximating in cross sectional shape an inverted truncated pyramid providing a space disposed inwardly of the vertical plane of the side of the rail and above the horizontal 35 plane of the head fillet of the rail, and a splice bar provided at its top with a formation of metal extending through said space.

40 5. A rail splicing structure including the rail having the bottom corners of its head truncated, a connecting splice bar having head and base fishing contact with the rail, and a formation of metal on the head of the bar extending into the space or area vacated by the truncations of the rail head.

In testimony whereof I hereunto affix my signature.

MCLEOD THOMSON.
